UNITED STATES PATENT OFFICE.

HARRY J. FARRINGTON, OF BOSTON, MASSACHUSETTS, ASSIGNOR TO FARRINGTON MANUFACTURING COMPANY, OF BOSTON, MASSACHUSETTS, A CORPORATION OF MAINE.

JEWELRY-BOX.

1,217,291.

Specification of Letters Patent. Patented Feb. 27, 1917.

Application filed March 1, 1916. Serial No. 81,532.

To all whom it may concern:

Be it known that I, HARRY J. FARRINGTON, a citizen of the United States, residing at Boston, county of Suffolk, State of Massachusetts, have invented an Improvement in Jewelry-Boxes, of which the following description, in connection with the accompanying drawing, is a specification, like characters on the drawing representing like parts.

- 10 This invention relates to an improvement in boxes and is more specifically directed to improvements in that general class of boxes which are employed in connection with the jewelry trade. The general object of this 15 invention is to construct a box or cover which is durable, of low cost, which is readily susceptible to pleasing and useful variations in conformation and which is adapted easily to be covered and padded.
- 20 A more specific object is to produce a box structure the parts of which may be suitably covered, or padded and covered, by means of the ordinary folding machines before assemblage into the completed whole.
- 25 Another object is to produce a box or cover the finished parts of which may be easily and quickly assembled into a completed whole by unskilled labor.

Other objects of the invention will appear 30 from the following specification and accompanying drawings and will be pointed out in the annexed claims.

A selected embodiment of this invention and a modification thereof, designed to carry 35 out the objects of the invention, have been shown in the drawings, but it is to be understood that the invention is not to be confined to the exact features disclosed as various changes may be made within its reasonable 40 scope. It will be readily seen and understood that the article as shown may be either a box-cover or the box itself. And, solely in the interest of clarity, such article is designated in the specification and claims as the 45 box portion. This invention comprehends the production of a box and its cover while, obviously, either one may be employed with a differently formed complement.

In the accompanying drawing:

50 Figure 1 is a perspective view of the improved structure;

Fig. 2 is a sectional view on the line 2—2 of Fig. 1;

55 Fig. 3 is a perspective view of a modification of the structure;

Fig. 4 is a sectional view on the line 4—4 of Fig. 3; and

Fig. 5 is an elevation of the fastener shown in Figs. 3 and 4.

In the selected embodiment shown in Fig. 60 1, a base 1, which is preferably formed of a plate or piece of sheet metal, is provided. This plate which is here shown as a plane surface of generally rectangular shape may be flat, convex, concave or of irregular shape 65 while its periphery may be waved or otherwise fancifully formed. The sides of the article are preferably constructed, as here shown, of a single strip 2 of material, although obviously, a plurality of strip members 70 may be employed. The ends of the strip 2 are joined together in the manner usual in this art. The strip material here shown is steel and an integral flange 3 is 75 provided upon the metallic strip. This flanged strip is thus substantially L-shaped with its short leg positioned upon the box base while the long leg upwardly projects to form the sides of the article. Although 80 steel is preferably used, due to its durability 85 and ease of manipulation to form the completed side strip, it is obvious that the strip may be fabricated of paper pulp suitably formed, or of fiber-board or similar materials in which the requisite qualities inhere.

A simple means of fastening the strip to the base is provided by punching, stamping, cutting or otherwise forming suitable projecting tabs on the base to extend from the base around the edge and down upon the 90 upper surface of the strip flange whereby the strip is clamped to the base. In the selected embodiment shown in Fig. 1, the tabs 4 are partially cut from the metallic base. While several of these tabs are shown it is 95 obvious that the desired function may be achieved by the employment of a greater or less number. When the base is in this state of completion, it may advantageously be covered. In the embodiment of Fig. 1, a piece 100 of relatively soft sheet material, such as card-board 5 or other padding is suitably secured to the bottom or outside of the base. A decorative covering 6 of cloth, paper, leather or similar material, is then secured 105 to the base, being usually glued or pasted thereto by means of the folding machines well known in this art. The peripheral end portions of the covering are turned over the ends of the base and backwardly turned 110

upon the upper face of the base so that the covering extends under the flange 3 of the positioned side strip. The strip being emplaced, the tabs are turned around the edge 5 and down upon the upper surface of the flange and function securely to engage clamp and retain the box sides.

The strip is also covered in a somewhat similar manner although the covering material 10 embraces both sides of the strip, and the padding or card-board 5 is secured between the inside face of the upwardly projecting strip and the inside portion of the material 6. The covering material is preferably not secured to the major portions of 15 the padding so that a puffed or padded feeling is imparted to the bottom and inside of the completed box or cover.

In the modification of this novel box or 20 cover structure shown in Figs. 3, 4 and 5, the invention is disclosed as applied to a structure having its base of such material that the fastening tabs may not be integrally formed. In this modification, the 25 base 7 is of wood, though obviously it may be of a suitably durable fiber-board or other material. A similarly flanged side strip 8 is employed. This strip may be of wood or fiber-board and may be likewise formed 30 in several pieces, suitably joined. Herein the flange 9 integral with the strip, is clamped by means of suitable flat metallic fasteners such as the ordinary glazier's tack 10. Each tack is driven through the base 35 before the similar padding 11 and the covering 12 are affixed. The apex of one angle of the tack, projecting upwardly through the base, thus also extends from the base and is bent around the edge and down upon 40 the upper surface of the strip flange and thus retentively engages and clamps the strip flange to the base and holds the side-forming strip in position. In Fig. 4, the strip is shown as unpadded while as in the 45 metallic structure the respective longitudinal ends of the strip covering are respec-

tively flush with the covering 12 on the projecting inner face of the base and with the upper face of the flange 9.

There is thus provided a box of simple 50 construction especially adapted for use in the jewelry trade. This construction is such that the component parts may readily be padded, if desirable, and covered with cloth, 55 paper, leather, or other media, by means of the ordinary folding machines, the fastening media being concealed on the outside of the article. When covered, the parts are easily clamped together by the tabs and the finished box is very pleasing to the 60 sight and the touch. The construction is durable, relatively inexpensive, of few parts and may be expeditiously assembled.

It is to be understood that the construction disclosed herein is illustrative but not 65 restrictive and that the same may be modified within the meaning and scope of the claims which follow.

Having fully described my invention, 70 what I claim as new and desire to secure by Letters Patent is:

1. In a box the combination of a base; a side forming strip projecting from, and presenting a flange positioned upon, said base; and a plurality of tabs extending from the 75 base around the edge, and down upon the upper surface, of the flange and acting to clamp and secure the said flange and base together.

2. In a box the combination of a metallic 80 base; a side forming strip projecting from, and presenting a flange positioned upon, said base; and a plurality of tabs partially cut from and integral with the base and extending therefrom around the edge, and 85 down upon the upper surface, of the flange and acting to clamp and secure said flange and base together.

In testimony whereof, I have signed my name to this specification.

HARRY J. FARRINGTON.
